UNITED STATES PATENT OFFICE.

ASHLEY GUY OGDEN, OF BALTIMORE, MARYLAND, ASSIGNOR TO THE MULTIPLE OFF-SET MACHINE COMPANY, INC., OF BALTIMORE, MARYLAND.

PRINTING DEVICE.

1,199,597.

Specification of Letters Patent. Patented Sept. 26, 1916.

Application filed October 9, 1915. Serial No. 55,046.

To all whom it may concern:

Be it known that I, ASHLEY G. OGDEN, a citizen of the United States, and a resident of the city of Baltimore, in the State of Maryland, have invented a certain new and useful Improvement in Printing Devices, of which the following is a specification.

My invention relates to printing devices for reproducing a multiplicity of prints arranged in symmetrical relation, from a single negative.

The present application is an improvement on the device which forms the subject of a prior application, Serial No. 37524, filed July 1, 1915. In said prior application I disclosed a device in which the prints were designed to be made so that the designs were accurately spaced in symmetrical relation.

The primary object of the present invention is to provide an improved device in which the accurate spacing of the design is easily accomplished. To this end I arrange a holding means for the negative from which the prints are to be made and have indicating devices which may be brought into registration with certain marks on the negative, and afterward be lifted therefrom, and again brought into position over another negative having similar marks, so that the latter marks may be brought into registration with the indicating devices.

A further object of my invention is to provide a means for more accurately adjusting the step by step device by means of which a sensitized plate is shifted from one position to another, with respect to a stationary negative.

Other objects and advantages will appear in the following specification, and the novel features of the invention will be particularly pointed out in the appended claims.

My invention is illustrated in the accompanying drawings forming part of this application, in which:

Figure 1 is a plan view of the device. Fig. 2 is a section along the line 2-2 of Fig. 1. Fig. 3 is a section along the line 3-3 of Fig. 1. Fig. 4 is a section along the line 4-4 of Fig. 1. Fig. 5 is a section along the line 5-5 of Fig. 1. Fig. 6 is a section along the line 6-6 of Fig. 1. Fig. 7 is a detail plan view showing the indicating de-

vices in registration with certain marks on the negative. Fig. 8 is a section along the line 8-8 of Fig. 7. Fig. 9 is a section along the line 9-9 of Fig. 7. Fig. 10 is a perspective view showing a modified form of the spacing device. Fig. 11 is a section along the line 11-11 of Fig. 10.

In carrying out my invention I provide a suitable bed plate 1 which is preferably made of metal. Secured to the underside of the bed plate is a U-shaped bracket 3 which is provided with slotted extensions 4 at each end thereof, arranged to receive the slotted ends 5 of a cross bar 6. The central portion of this cross bar 6 bears a pair of upstanding bracket members 7, see Fig. 3, in which the cylindrical ends 8 of a cam member 9 are journaled. As will be seen from Fig. 2, this cam member is circular, but the journaled portions 8 are disposed off-center. The edge of the cam member 9 is arranged to bear upon a plunger 10 which passes through the body portion of the cross bar 6 and which bears a swiveled head 11 faced with some resilient material 12, such as rubber or the like. A handle 13 is provided for manipulating the cam 9. It will be seen that on turning the handle in the direction indicated by the curved arrow in Fig. 2, the plunger 10 with its resiliently faced head 11 will be forced downwardly against a plate 14.

At diagonally opposite corners of the head 11 rods 15 pass through the plate 6 and are connected to the head, springs 16 being provided above the plate, these springs exerting tension on the rod 15 so as to cause the plate 11 to be lifted when the handle 13 is thrown over into the dotted line position shown in Fig. 2.

The plate 1 is provided with an opening 17, see Fig. 2, this opening being bordered by shoulders 18 upon which the transparent negative-supporting plate 19 rests. The base plate 1 is provided with upwardly extending flanges 20. The negative 22 may be adjusted and held in its adjusted position by means of set screws 23 which pass through the flanges 20 and engage the edges of the negative as shown in Figs. 1, 2, 3, and 7.

Referring now to Fig. 1, I have shown

therein a rectangular frame 24, one side of which is provided with a rack 25. The frame 24 as will be seen from Fig. 2, has a V-shaped bottom which rests in a groove 25 in the base plate 1, thus permitting the frame 24 to slide relatively to the base plate. A cross bar 26 is carried by the frame 24 and is provided with a V-shaped groove 27 arranged to receive a bar 28 which is slidable in the groove. Secured to the bar 28 by means of set screws 29^a are the clamping members 29, see Fig. 6, and to each clamping member is pivotally connected a grooved arm 30, the grooves in 15 the arms 30 facing each other in order to receive and hold the sensitive plate 14. A cross member 31 is provided for holding the outer ends of the arms 30 in spaced relation. Holes 32 are provided for shifting 20 the position of the cross member 31 with respect to the arms 30. Set screws or pins 33 are provided for holding the cross member 31 in position. The clamping member 29 may be shifted along the bar 28 by loosening the set screws 29^a.

Carried by the base plate 1 is an extension 1^x which is provided with a pair of parallel grooves 1^y, see Fig. 5, arranged to receive tongues of a bracket 35 which bears 30 a screw 36 having its ends swiveled into a pivoted clamping member 37 adapted to engage the teeth 25 of the side member of the frame 24, so as to clamp the bracket 35 securely to the side member in adjusted position. An extension 38 of the bracket 35 is arranged to engage a stop member 40, or the end of a micrometer screw 41 which is threaded at 42 in a fixed portion of the extension 1^x. The purpose of this construction will be explained later.

The plate 26 has an extension 26^x which is provided with a micrometer 43 and with an adjustable stop member 44 adapted to engage the micrometer screw 43 in the same 45 manner that the stop member 38 engages the micrometer screw 41.

In Figs. 1 and 4 I have shown a means for shifting the frame 24. This consists of a hand wheel 45 which is connected with 50 the pinion 46 in mesh with the rack 25 of the frame 24. The turning of the hand wheel will obviously shift the rack in either direction.

In executing very fine work it is sometimes necessary to center the negative with extreme accuracy, and to this end I provide a cut-away portion 1^c of the base 1 in which is disposed a U-shaped frame 47 whose sides are coextensive with the flanges 20. 60 This U-shaped frame is hinged at 48 and bears pointers 49 which are slotted as shown at 50 and which are provided with screws or pins 51 which permit the pointers to be moved inwardly or outwardly and to

be clamped in different angular positions 65 with respect to the side members of the frame.

From the foregoing description of the various parts of the device, the operation thereof may be readily understood.

A negative 22 is made and is placed in position upon the transparent plate 19 just above the opening 17. As will be seen from the drawings there is a light housing 52 in which an incandescent light 53 is disposed 75 so that the light shines directly on the plate 19 bearing the negative. The plate 14 having a sensitized surface is now placed in the frame formed by the grooved arms 30 and the cross member 31, the distance between 80 the arms 30 being adjusted in the manner described to retain the sensitized plate in position. The position of the plate is adjusted so that the negative is preferably located adjacent to one corner of the plate in 85 beginning the operation. The handle 13 of the clamping device is now swung to the full line position shown in Fig. 2, thus clamping the plate down upon the negative, when an exposure may be made. After the 90 exposure the handle 13 is swung to the dotted line position shown in Fig. 2, thus unclamping the plate. The micrometer devices carried by the extension 1^x and 26^x may be adjusted so as to permit a movement of 95 the frame 24 and of the arms 30 at right angles to the movement of the frame 24 to any desired distance, and this distance is very accurately gaged because of the fact that a micrometer is employed. The stop 100 members 38 and 44 may be adjustably secured to the frame 24 and the rod 28 respectively in the manner already described. An exposure is made and then the stop member 44, for instance, may be shifted the distance between the jaws of the micrometer. 105 and the device may be again attached to the bar 28 so that when the frame is moved the sensitized plate will be carried a given distance and no farther. Similarly the stop member 38 may be shifted from one point, as for instance from the end of the screw 42 to the end of the stop member 40 and again secured to the frame, so that when the frame is moved it will be moved a given 110 distance, or the distance between the screw 42 and the stop member 40. In this manner, a row of prints may be taken and then another row and additional rows, all of which contain prints which are symmetrically spaced, this spacing being very accurately gaged. It is obviously immaterial 115 whether the prints are made in rows or columns.

In certain instances it is of great importance to have the negative accurately positioned, and to this end the indicating device already described is provided. It will be 125

observed that the negative 22, in Fig. 1, has indicating marks or points. If now this negative is to be removed and another one, either larger or smaller, replaced, it may be 5 desirable to have the second negative in the same relative position as in the first one. This second negative would have marks 22^a corresponding to the marks shown in the drawing. Prior to the removal of the first 10 negative, the frame 47 bearing the indicating devices 49, was swung on its hinges and the points of the indicating devices 49 were made to register with the marks 22^a as shown in Fig. 7. The frame 47 is now swung back 15 into its original position, and when the second negative is substituted for the first, the frame is again swung over so that the pointers will indicate where the second negative is to be placed. The adjustment of the 20 negative is accomplished by means of the screws 23. Obviously the pointers 49 may be shifted so as to register with any point on the negative so that if the latter is removed and replaced it may be replaced in 25 exactly the same position.

In Figs. 10 and 11 I have shown a modified form of the spacing mechanism. In this form a clamping member which I have denoted in general by 54 and which bears a 30 stop member 54^a, may be secured to the slidable frame 24, the member 54 sliding on the base 1 in the manner shown in Fig. 11. At 55 and 55^a I have shown two stop members which, as will be seen, are dove-tailed 35 into a groove 56 in the extension 1^x, each of these stop members being provided with a set screw 57 for clamping it in position. The beveled edge of a scale 58 furnishes means whereby the distance between the stop 40 members 55 and 55^a may be accurately gauged.

It is obvious that the frame 24 may be moved either by hand or by the wheel 45, while the bar 28 is preferably moved by 45 hand.

I claim:

1. In a printing device, a base, a source of light carried thereby, a negative carried by said base and disposed within the field 50 of said source of light, a frame mounted on said base, means for shifting said frame relatively to said negative in two directions at right angles to each other, means on said base for adjusting the position of the negative with respect to the base, and indicating 55 means connected to the last named means for indicating the precise position to which the negative is adjusted.

2. In a printing device, a base, a source 60 of light carried thereby, a negative, means carried by said base for adjustably holding said negative, and indicating means carried by said base and adapted to be brought into registration with portions of the negative

for indicating the position of the negative 65 with respect to the base, a frame on said base for adjustably supporting a sensitized plate, and means for shifting said frame relatively to said negative.

3. In a printing device, a base, a source 70 of light carried thereby, a negative, means carried by said base for adjustably holding said negative within the field of said source of light, a frame on said base for adjustably supporting a sensitized plate, means 75 for shifting said frame relatively to said negative, and an indicating device hinged to said frame, adapted to be brought into registration with portions of the negative 80 for indicating the position of the negative with respect to the base.

4. In a printing device, a base, a source of light carried thereby, a negative, means carried by said base for adjustably holding said negative within the field of said source 85 of light, a frame on said base for adjustably supporting a sensitized plate, means for shifting said frame relatively to said negative, and a hinged frame having an adjustable indicating member adapted to be 90 brought into registration with certain portions of the negative for indicating the position of the negative with respect to the base.

5. In a printing device, a base, a source 95 of light carried thereby, a negative, means carried by said base for adjustably holding said negative within the field of said source of light, a frame on said base for adjustably supporting a sensitized plate, means for shifting said frame relatively to said negative, a frame hinged to the first named means, a plurality of adjustable pointers carried by said hinged frame, the ends of 100 said pointers being adapted to register with portions of the negative whereby the relative position of the negative with respect to the base may be recorded.

6. In a printing device, a base, a source 105 of light carried thereby, a negative, means carried by said base for adjustably holding said negative within the field of said source of light, a frame on said base for adjustably supporting a sensitized plate, means for shifting said frame relatively to said negative, a frame hinged to first named 115 means, a plurality of pointers carried by said hinged frame, each of said pointers being provided with a longitudinal slot, a set screw arranged to enter said slot, said pointers being pivotally and longitudinally 120 movable with respect to said set screw.

7. In a printing device, a base, a source 125 of light carried thereby, a negative adjustably carried by said base and disposed within the field of said source of light, a frame on said base for adjustably supporting a sensitized plate, means including a stop member carried by the frame and a mi-

crometer carried by the base for moving said frame a predetermined distance.

8. In a printing device, a base, a source of light carried thereby, a negative adjustably carried by said base and disposed within the field of said source of light, a frame on said base for adjustably supporting a

sensitized plate, a stop member adjustably secured to said frame, a screw micrometer secured to said base, said stop member being normally disposed between the jaws of said screw micrometer and adapted to limit the movement of the frame.

ASHLEY GUY OGDEN.
